DEVICE FOR USING ADHESIVE TAPE

George H. Fritzinger, West Orange, N. J., assignor of one-half to Harold G. Kendall, Brooklyn, N. Y.

Application May 13, 1946, Serial No. 669,241

24 Claims. (Cl. 216—23)

1

This invention relates particularly to devices for dispensing and applying pressure-sensitive tape, and more especially to novel die mechanisms and novel combinations of die and tape-feeding mechanisms for such devices.

Different features embodied in the devices herein particularly shown and described are described and claimed broadly in my pending applications Serial No. 467,616 filed November 28, 1942 (now Pat. No. 2,437,022), Serial No. 551,769 filed August 29, 1944 (issued June 4, 1946, as Pat. No. 2,401,298, and now reissued as Re. 22,972) Serial No. 627,997 filed November 13, 1945, issued November 1, 1949, Patent No. 2,486,470, and Serial No. 635,890, filed December 19, 1945, issued November 1, 1949, as Patent No. 2,486,471.

This invention is particularly, among other things, an improvement on the punching and reinforcing machines of the character disclosed in my aforementioned pending applications Serial Nos. 551,769 and 635,890.

It is an object of my invention to provide a novel die mechanism for punching and reinforcing machines of the character mentioned which is adapted to render those machines universal in that it permits the distance of the punched holes from the edge of the sheet to be readily varied.

It is another object to provide a novel die mechanism for such machines which enables the machines to be constructed more cheaply.

It is another object to provide a novel die mechanism for cutting adhesive tape.

It is another object to provide a novel die mechanism which is adapted for applying strips of pressure-sensitive tape anywhere on flat surfaces.

It is another object to provide a novel device for dispensing strips of adhesive tape and applying the same to flat surfaces.

These and other objects and features of my invention lie in the details of construction, arrangements of parts and combinations of elements in the embodiments herein particularly described, and will be apparent from the following description and the appended claims.

In the description of my invention reference is had to the accompanying drawings, of which:

Figure 1 is an elevational view of a unit for punching and reinforcing sheets according to my invention, certain parts being shown in operated positions by dash-dot lines;

Figure 1a is a partial elevational view of the die mechanism, itself, of my invention;

Figure 2 is a front elevational view of this unit;

Figure 3 is a top plan view of this unit;

2

Figure 4 is a fractional section taken substantially on the line 4—4 of Figure 1;

Figure 5 is a fractional section taken substantially on the line 5—5 of Figure 1;

5 Figure 6 is a side elevation of a device, in unoperated condition, according to my invention for applying strips of pressure-sensitive tape to flat surfaces;

Figure 7 is a front elevational view of the device of Figure 6;

Figure 8 is a view similar to Figure 6 but showing the device in its operated condition;

Figure 9 is a fractional section taken substantially on the line 9—9 of Figure 6; and

15 Figure 10 is a fractional section taken substantially on the line 10—10 of Figure 6.

The embodiment shown in Figures 1 through 5 consists of a single unit 10 adapted particularly for feeding out lengths or strips of pressure-sensitive tape from a supply roll 11, applying those lengths to sheets, one of which is indicated at 12, and for punching the laminated sheet-tape portion, all in one operation by depressing a pivoted handle 13. This unit is intended particularly for punching and reinforcing paper sheets for loose-leaf binders, but it obviously has other uses. While only a single unit is herein shown, it will be understood that any number of these units may be incorporated in a single machine and worked simultaneously as illustrated in my pending applications abovementioned.

The unit 10 has a vertical frame plate 14 at its left side which has portions thereof bent over at right angles thereto of which there is a lower forward portion bent over and upwardly to form a lower die plate 15 on which is placed the sheet 12, a portion directly above this die plate which is bent over and upwardly to provide a clearance space 16 above the die plate and which portion 20 is apertured to form a bearing 17, and a top portion which is bent over and downwardly and which is also apertured to form a bearing 18 vertically in line with the bearing 17. Also, the frame plate has a rearward lug 19, and a leg 23 25 depending from the die plate 15, both of which seat on and are secured to a base plate 21. Below the die plate 15 there is thus a clearance space 22 for collecting the punchings as will herein-after appear. This frame plate with its bent-over portions herein described is suitably formed by stamping.

Mounted slidably in the bearings 17 and 18 is a tubular plunger 23 to the lower end of which there is staked a presser die plate 24. This die plate 55 is arranged to engage the lower die plate 15 in

parallel relation when the plunger is advanced—i. e., depressed—and has a cutting edge 24a along its rearward side (as with respect to the unit). At this rearward side of the presser plate 24 there is a blade 25 having a cutting edge 25a which is directly below the edge 24a for engagement with the latter when the plunger 23 is depressed. Preferably, the blade 25 is mounted slidably on the portion 15a of the lower die plate which is to the rear of the presser plate 23, for front and back rectilinear movement—i. e., inward and outward movement relative to the presser plate. Also, the blade is spaced from the lower die plate 15 so as to provide a clearance space 26 therebelow to permit the sheets 12 to be inserted into the unit beyond the cutting edge of the blade. In order to so mount the blade a flat spacer plate 27 is secured to the die plate portion 15a and the blade is secured slidably onto this spacer plate by a headed screw 27a that passes through a slot 28 in the blade (Figure 4). The blade lies in a channel of which the frame plate 14 forms the left side and a bar 29, secured by screws 30 to the die plate portion 15a, forms the right side. Accordingly the blade is confined to rectilinear front and back movement. The blade has a turned-up lug 25b at its rear end against which bears a spring 31, that is secured to the frame plate, to urge the blade forwardly. At the front of the lug 25b there is a lug 32 turned up from the spacer plate 27, which passes through a clearance opening 33 in the blade and through which there is threaded a stop screw 34 that abuts against the lug 25b to define the most forward or innermost position of the blade. The cutting edge 25a of the blade is inclined downwardly relative to the presser plate (Figure 2) and is also inclined inwardly with respect to a vertical plane through the cutting edge 24a, when proceeding from the highest to the lowest point of the blade (Figure 4). Thus, when the blade is properly set by the stop screw 34, it is engaged by the edge 24a in scissors relationship—i. e., with a progressive point contact, with the blade being cammed slightly rearwardly by the presser plate, to give a very positive cutting action.

The tape-feeding mechanism, which is substantially the same as is described in my aforementioned pending application S. N. 635,890, is adapted for pulling successive lengths of pressure-sensitive tape from the roll 11 past the cutting edges 24a and 25a and into the space between the die plates with the adhesive side of the tape facing downwardly towards the lower die plate and blade. This mechanism comprises a backing member 35 which overlies the presser plate 24 and extends rearwardly thereof. A portion of this rearward part of the member 35 is covered by a rubber tubing to provide a yieldable surface or anvil 36 for backing the non-adhesive side of the tape. The member 35 has an apertured U-shaped forward part 35a which straddles the bearing 17 and is slidably mounted on the plunger 23. However, the member 35 is normally held against the presser plate by a compression spring 37 which surrounds the plunger and bears against the part 35a thereof. Below the anvil 36 there is a feed member 38 which has a smooth flat surface engaging the adhesive side of the tape supply. This feed member has left and right arms 38a and 38b which straddle the anvil 36 and frame plate. These arms are pivoted on a horizontal axis above the tape-engaging surface thereof, at 39, to respective forwardly-

extending arms 40a and 40b of a horizontal bifurcated lever 40. This lever straddles the unit and has a bridge 40c interconnecting the arms thereof, which passes through the clearance space 22 at the rear of the lower die plate 15. The lever 40 is carried pivotally by a vertical bifurcated lever 41 which straddles also the unit. This lever has depending legs 41a and 41b connected by a bridge 41c at the top. These legs are pivoted at their lower ends, as at 42, to the arms 40a and 40b respectively of lever 40. The lever 41 is pivoted at 43 to a post 43a secured to the upper part of the frame plate.

The lever 40 is urged clockwise (Figure 1) by a tension spring 44 connected to the left arm thereof so as to bias the feed member against the anvil 36. When the lever 41 is swung forwardly the feed member is directed obliquely away from the anvil in response to a counterclockwise rocking of the lever 40 caused by the engagement of a pin 45 on the rear end of the arm 40a thereof with a cam 46 that is secured to the frame plate. As the feed member is so moved from the anvil it is freed from torsional restraint and is turned counterclockwise (Figure 1) by the resisting feed force of the tape caused by the adherence of the tape to the supply roll. This turning of the feed member reduces the feed angle—the angle between the engaging surface of the feed member and the adhesive side of the tape leading therefrom—to less than 180 degrees and causes the feed member to take a tenacious hold on the tape as explained in my aforementioned application S. N. 551,769. Thus, as the feed member is advanced it draws a length of tape from the roll into the space between the two die plates. As it nears the end of its forward stroke, the left arm of the feed member impinges against a pin 47 on the frame plate and is turned clockwise to increase the feed angle to more than 180 degrees and thereby release the hold of the feed member on the tape.

In order that the feed member will be released positively from the tape at the end of the feed stroke, the roll is locked as the feed angle is increased to more than 180 degrees and before the feed member reaches its final position—the position shown in dash-dot lines in Figure 1—as described and claimed in my pending application S. N. 627,997, filed November 13, 1945. To this end the roll is mounted on a ratchet disk 48 that is journaled at 49 to the frame plate. The roll is held releasably to the disk by two spring arms 50 which engage the annular core 11a of the roll, and is locked against turning on the disk by two lugs 51 which engage slits in the core 11a. Mounted adjustably on the bridge 41c of the lever 41 is a latch pawl 52 which overlies the ratchet disk. This pawl is so adjusted on the lever 41 that as the lever is swung forwardly the pawl will engage the ratchet disk, and lock the roll, in the final part of the feed stroke.

Pivoted at 53 to the lever 41 is a link 54 which in turn is pivoted at 55 to an upstanding arm 56a of a drive member 56. This drive member is splined to a cross shaft 57 that is journaled in a bearing 58 of the frame plate. The handle 13 is secured to one end of this shaft. As the handle is depressed the lever 41 is swung forwardly to advance the feed member. Because of a decreasing effective leverage of the arm 56a the feed member is moved through the major part of its advance stroke as the handle is moved through the first half of its downward stroke and is

moved relatively little as the handle is moved through the remainder of its downward stroke.

The drive member 56 has a second arm 56b which works between two pins 59 and 60 in the plunger 23. During approximately the first half part of the downward stroke of the handle this arm maintains contact with the upper pin 59 and retains the plunger in its raised position. In the last half part of the downward stroke of the handle the arm 56b impinges against the lower pin 60 and drives the plunger downwardly to close the die plates, with the arm now working between the two pins 59 and 60. Conversely, as the handle is raised, the plunger is first positively raised to open the die plates by the sliding contact of the arm 56b with the pin 59, and then the feed member is returned to initial position. This forced sequential operation of the feed and die mechanisms prevents the presser plate 24 from ever obstructing the feed member in its advance and return movements.

Mounted slidably within the plunger 23 is a punch 61. The upper pin 59 passes through a clearance slot 59a in this punch but the lower pin 60 is secured to the punch and passes through a clearance slot 60a in the plunger all so that the punch will have a limited freedom of movement relative to the plunger. The aforementioned spring 37 is interposed between the pin 60 and the part 35a of the member 35 and holds the punch normally in a raised or retracted position with respect to the presser plate 24. As the handle is depressed the plunger is driven by an actuating force transmitted through the spring 37, but when the presser plate engages the lower die plate this spring yields to a further downward force on the handle to cause the punch to be projected through a hardened annular insert 62 in the lower die plate so as to punch a hole through the sheet and the tape applied thereto, the blank which is so punched out falling into the space 22 below the lower die plate. During the initial return movement of the handle, the spring 37 retracts the punch and disengages it positively from the sheet.

During the initial closing of the die mechanism, the anvil 36 is first moved unitarily with the presser plate 24 by the spring 37 until it reaches a position near the blade 25, shown by dash-dot lines in Figure 1, where it is stopped positively by the abutment of the part 35a against the bearing 17. Thereafter, during the final closing of the die mechanism, the presser plate is moved past the blade and into contact with the lower die plate with the spring 37 being compressed. As the die mechanism is opened, the anvil remains stationary until the presser plate 24 reaches the member 35 and then the presser plate and anvil return together.

In the interim between the time the fed-out length of tape is cut free from the tape supply and the time the feed member is returned to its initial position, the tape drawn from the roll is retained slidably to the anvil by a finger 63a of a spring member 63 that is secured to the member 35 at the rear of the anvil. This spring member bears slidably against the frame plate 14 to hold the anvil from turning in one direction about the plunger. At the front of the plunger the member 35 contacts slidably the frame plate to hold the anvil from turning in the other direction.

Turned up from the presser plate at the left rearward part thereof there is an arm 64 which passes through clearance slots 65 in the bearing

17 and part 35a of the member 35. This arm extends rearwardly, at a suitable clearance distance above the anvil 36, along the right side of the frame plate 14, and is retained slidably against 5 the frame plate, to prevent the presser plate from turning in the bearings 17 and 18, by an offset bar 66 secured by screws 67 to the frame plate.

As the tape is severed the adhesive side of the tape supply contacts the blade 25. However, in 10 order that this contact will be limited to the edge 25a of the blade, the inner end of the blade bearing the edge 25a is turned upwardly as shown in Figure 1. By the present invention, even the adhesive contact of the tape supply with the edge 15 25a is broken positively before the anvil is begun to be returned to its initial position. This is done by retracting the tape supply a short distance during the advance of the presser plate beyond the blade 25. Preferably the tape is so retracted by providing the arm 64 with a finger 64a that will traverse the path of the tape supply from the roll to the anvil during the final part of the advance movement of the presser plate. To this end the tape supply is given a definite path 20 by drawing it from the roll around a roller 68 that is journaled to the frame plate, and the finger 64a is positioned to move against the tape from the ungummed side between the roller and the anvil to withdraw the tape past the finger 63a. By retracting the tape it is assured that the tape supply in advance of the finger 63a will 25 be held adjacent to the anvil so that the feed member will engage it properly when it is returned to initial position.

35 During the return stroke of the feed member it is moved in a path at a substantial distance below the anvil 36, so that it will well clear the tape supply ahead of the spring finger 63a, and then when it reaches its most rearward position 40 it is snapped upwardly against the tape supply by the spring 44. The downward path of the feed member during the return stroke is defined by the pin 45 sliding on a flat spring 70, which overlies the cam 46 and is held to the frame plate 45 by screws 70a, to rock the lever 40 counterclockwise. Also, during the final part of the return stroke the feed member is turned counterclockwise to its initial upright direction (in respect of its arms) by the impingement of the left 50 arm thereof against a pin 71 on the frame plate, the final angular positioning of the feed member being defined by the contact of the left arm with the pin 71 and by contact of the lower part of the feed member with the vertical edge 55 72 of the feed member at the rear of the clearance opening 16. The feed member is however prevented from bearing with pressure against the pin 71 and edge 72 by a stop lug 73 on the frame plate for the lever 41. As the lever 41 60 comes against this stop lug the pin 45 moves into registration with a slot 74 in the spring 70 to free the lever 40 from torsional restraint so that the spring 44 can snap the lever 40 clockwise and move the feed member against the tape 65 supply.

At the sides of the unit there are members 75 each of which has a slotted base portion mounted on and held adjustably to the base 21 by a screw 76. Each member 75 has an upright arm 75a 70 which extends slightly above the lower die plate 15 and then terminates in a forwardly- and upwardly-curved finger 75b. These fingers serve to deflect the sheets 12 downwardly across the die plate 15 and into the clearance space 26 as 75 they are inserted into the unit, and the arms

15a serve as a stop for limiting the distance the sheets can be inserted. If it is desired to change the distance of the punched hole from the edge of the sheet, it is only necessary to loosen the screws 16, shift the members 15 forwardly or rearwardly to the desired positions and tighten the screws.

The embodiment shown in Figures 6 through 10 is adapted for applying strips of pressure-sensitive tape to flat surfaces. This embodiment has a left side frame plate 80 having a bottom portion bent over to the right (Figure 7) to form a base 81. A portion of the frame plate above the base is bent over and upwardly, and is apertured, to form a lower bearing 82 and a top portion of the frame plate is bent over and downwardly, and also apertured, to form an upper bearing 83 vertically in line with the lower bearing 82. In the side frame plate below the bearing 82 and extending to the front and rear thereof is a clearance opening 84 (Figure 6) and in the base below the bearing 82 is a clearance opening 85 (Figure 9) the functions of which are hereinafter explained.

Slidably mounted in the bearings 82 and 83 is a tubular plunger 86 to the lower end of which there is secured a presser die plate 87 having a cutting edge 87a along its rearward side. This presser plate is preferably faced with a resilient pad 88 as of sponge rubber. As the plunger is depressed the edge 87a of the presser plate engages a forward edge 89a of a blade 89 that is slidably mounted on the base 81 at the rear of the presser plate, the blade being interposed between the frame plate 80 and a bar 90 at its right side, which is secured to the base by screws 91, so as to confine the blade to rectilinear movement. The blade is retained slidably to the base by a shouldered screw 92 which is threaded in the base and which passes through a slot 93 in the blade to allow the blade a limited movement. The blade has a turned-down lug 89b at its rear end engaged by a spring 94, which is secured to the frame plate by screws 95, to urge the blade forwardly. The blade is limited in its biased direction by a stop screw 96 that is threaded through the lug 89b and which may engage the rear edge of the base 81. However, in order to provide an additional clearance below the blade for the stop screw there is interposed a spacer plate 97 between the blade and base 81, which spacer plate has a turned-down lug 97a at its rear end that is engaged by the stop screw and pressed against the rear edge of the base.

The forward end of the blade overhangs slightly the clearance opening 85 in the base 81. As the plunger is depressed the presser plate first engages the blade in scissors relation, to cut the tape as will hereinafter appear, and then passes through the clearance opening to move against the object on which the device is seated.

The tape-feeding mechanism, except for its actuating means, is substantially the same as that shown in the foregoing embodiment. This mechanism comprises a tape-backing member 98 which has a U-shaped forward portion that straddles the lower bearing 82 and is slidably mounted on the plunger 86, and has an arm 98b extending rearwardly of the presser plate on which there is a rubber tube to provide a resilient surface or anvil 99. As in the foregoing embodiment, this backing member may be biased against the presser plate by a compression spring 100 surrounding the plunger. The tape is drawn from a supply roll 101 around a roller 102 that is

journalled to the frame plate, and is retained slidably to the anvil 99, with the adhesive side thereof facing downwardly, by a spring finger 103a of a spring member 103 that is secured to the backing member at the rear of the anvil. This spring member bears slidably against the frame plate to hold the backing member from turning in one direction about the plunger, the backing member being held from turning in the other direction by slidable contact of a forward part thereof also with the side frame plate.

Engaging the adhesive side of the tape backed by the anvil 99 is a feed member 104 which passes through the clearance opening 84 and which has left and right turned-up arms 104a and 104b that straddle the backing member and frame plate. These arms are pivoted at 105 to the forward arms of a horizontal bifurcated lever 106, the lever having a bridge 106c at its rear end which interconnects its two arms. The lever 106 is pivoted at a point 107 midway its length to an inverted bifurcated lever 108 that is pivoted at 109 to lugs 110 and 111 turned up from the upper bearing 83 at the back of the plunger 86. This lever 108 has left and right legs 108a and 108b which are interconnected by a bridge 108c at the front of the plunger.

The feed mechanism is actuated by swinging forwardly the lever 108 to move the feed member 104 forwardly past the presser plate 87. As before, the feed member is first moved obliquely downwardly from the anvil 99 and then forwardly in a direction substantially parallel to the presser plate until it is in a position ahead of the latter as shown in Figure 8. In its return movement, the feed member is guided in a path at a clearance distance below the anvil 99 and is then snapped upwardly against the tape supply backed by the anvil. To these ends the lever 106 is biased clockwise (Figure 6) by a tension spring 112 connected between it and the lever 108, and is provided with a pin 113 at its rearward portion, which rides on a V-shaped cam 114 secured to a rearward arm 115 of the frame plate, this arm being at a distance above the base 81 so as to provide a clearance space therebelow for the bridge 106c of the lever 106. Biased against the top side of the cam is an upwardly-inclined flat spring 116, held by screws 116b to the arm 115. During the forward stroke the pin 113 rides across the cam to guide the feed member as above explained, and during the return stroke the pin rides up on the spring 116 to space the feed member below the anvil 99. In this spring there is a slot 116a which clears the pin 113 when the feed member is at the end of its rearward movement defined by the abutment of the leg 108a of lever 108 against a stop lug 80a of the frame. When the pin registers with this slot, the spring 112 moves the lever 106 clockwise to snap the feed member against the tape supply backed by the anvil.

In its initial forward movement the feed member is turned counterclockwise so as to reduce the feed angle to less than 180 degrees to obtain a tenacious hold to the tape, and in its final forward movement the left arm of the feed member impinges against a pin 117 on the frame plate to turn the feed member clockwise so as to increase the feed angle to more than 180 degrees and release its hold on the tape. In the return movement of the feed member it is restored to its initial upright position (in respect of its arms) by the engagement of the left arm thereof with a pin 118 on the frame plate and

by contact of the lower part of the feed member with the vertical edge of the frame plate at the rear of the clearance opening 84.

At the end of the forward feed stroke the tape roll is locked so as to break positively the hold of the feed member on the tape. To this end the tape roll is mounted on a pair of spring arms 119 carried by a ratchet disk 120, and is locked against turning relative to the disk by two lugs 121 on the disk which engage slots in the annular core of the roll. The disk is pivoted at 122 to a spacer 123 on the side frame plate. The locking of the roll is effected by a spring latch pawl 124 that is mounted adjustably on an arm 108d of the lever 108. When the lever 108 is swung forwardly, this pawl is swung downwardly to engage the disk 119, and lock the roll, near the end of the forward feed stroke.

The actuating means for the feed and die mechanisms comprises a rod 125 mounted slidably in the plunger 86. This rod extends above the plunger and has a head 126 at the top so that it may be depressed easily by the palm of the hand. The rod 125 terminates about midway the length of the plunger, at 127, and has secured to the lower portion thereof a cross pin 128 that passes through vertical slots 129 in the plunger and through two identical cam slots 130 in the legs 108a and 108b respectively of the lever 108; also, this pin passes through a vertical clearance slot 131 in the side frame plate. The cam slots are curved so that as the head 126 is depressed through the major part of its stroke the lever 108 is swung forwardly to actuate the feed mechanism, but the lower portions of the cam slots are nearly straight so that the feed mechanism is held substantially stationary in its actuated position during the final part of the downward stroke of the head. As the head is raised, the lever 108 is cammed back to restore the feed mechanism to its initial position.

Below the rod 125 there is a cross pin 132 which is secured to the plunger and which also registers with the slot 131 in the frame plate. When the rod 125 reaches an intermediate position in its downward stroke—a position wherein the feed mechanism is substantially actuated—it strikes against the pin 132. In the further downward movement of the rod the plunger 86 is moved unitarily therewith. This causes the anvil 99 to be moved downwardly until the backing member 98 strikes against the bearing 82 and the presser plate to be moved onwardly past the blade 89 and through the opening 85 in the base 81 (see Figure 8).

The presser plate 87 has an arm 140 at the left side which extends upwardly above the anvil 99 and then rearwardly to a position between the anvil and the roller 102. Above this arm is a bar 141 held by screws to the frame plate which has an offset lower portion that slidably embraces the arm to hold it slidably against the frame plate and prevent the presser plate from turning. At the rear end of this arm 140 is a finger 142 which traverses the path of the tape from the roller 102 to the anvil 99, during the movement of the presser plate beyond the blade 89, to break the adhesive contact of the tape with the blade (see Figure 8).

The feed and die mechanisms are intercoupled so that the presser plate 87 cannot be lowered until the feed mechanism is nearly fully actuated, and so that the feed mechanism cannot be returned until the presser plate is nearly returned

to its raised position. The intercoupling mechanism comprises a member 133 which is pivoted on the cross pin 128 between the plunger and the side plate. This member has a straight arm 133a provided with a slot 134 which is engaged slidably by a pin 135 on the frame plate. Also, the member has a hook 133b depending from the rearward end thereof, which contacts slidably the underside of the pin 132. When the rod 125 is depressed the member 133 is turned clockwise about the cross pin 128. The hook 133b is so shaped that it just maintains contact with the pin 132, to hold the presser plate in its raised position, while the rod is moved downwardly against the pin. In the final part of the downward stroke wherein the plunger is moved unitarily with the rod 125, an arcuate edge 136 of the hook 133b swings past the underside of the pin 132 so that the hook interlocks the plunger to the rod. Accordingly, in the initial part of the return stroke of the rod the presser plate is moved positively therewith but in the final part of the upward stroke of the rod following the impingement of the backing member against the lower bearing 82 the rod is raised relative to the plunger with the hook 133b maintaining contact with the pin 132 and holding the presser plate raised. This forced sequential operation of the feed and die mechanisms is adapted to prevent them from obstructing one another.

The rod 125 is biased into raised position by a tension spring 137 connected between the upper bearing 83 and the member 133 so that the feed and die mechanisms will be returned automatically when the hand is removed from the head 126. The spring 137 is connected to the member 133 at a point midway the length of the arm 133a so as to reduce the amount of stretch required of the spring.

Normally this applying device is worked by setting it on whatever object it is desired to apply a strip of tape and then depressing the head 126, as in the manner of working the usual stapler, with that object taking up the force exerted against the head. In cases where the object is of a weak or fragile nature and cannot stand any substantial force exerted thereagainst, the device may be provided with side arms 138 near the top (Figure 7). These arms may be gripped by the fingers while the head 126 is in the palm of the hand so that the head may be depressed by closing the grasp of the hand without exerting any substantial force against the object.

I have herein particularly shown and described certain preferred embodiments of my invention, but it will be understood that these embodiments are illustrative and not limitative of my invention as the same are subject to changes and modifications without departure from the scope of my invention, which I endeavor to express according to the following claims.

I claim:

1. In a device for dispensing strips of pressure-sensitive tape from a supply roll and for applying said strips: the combination of a closable die mechanism comprising a presser member having a cutting edge at one side thereof, a blade having a cutting edge spaced from said presser member and adapted to engage said edge of said member in scissors relation when the die mechanism is closed; and a tape feeding means movable through the space between said cutting edges and arranged for pulling lengths of pressure-sensitive tape from said roll across said presser member

with the adhesive side of the tape facing away from said member.

2. In a device for dispensing strips of pressure-sensitive tape from a supply roll and applying said strips: the combination of a presser member having a cutting edge at one side thereof; a blade spaced from said presser member and mounted at said one side of said presser member for movement in directions transverse to the direction of spacing of said blade from said presser member; means mounting said presser member and blade for opening and closing movement; and a cutting edge on said blade engaged in scissors relation by said edge of said presser member when said presser member and blade are closed.

3. In a device for applying strips of pressure-sensitive tape: the combination of a die presser plate having a cutting edge at one side thereof; a blade at said one side of said presser plate and substantially parallel to said plate; means mounting said plate and blade for relative opening and closing movement in directions substantially at right angles to said plate; means slidably mounting said blade for rectilinear movement substantially parallel to said plate and in directions inwardly and outwardly with respect thereto; means biasing said blade inwardly; stop means for defining the innermost position of said blade; and a cutting edge on the inner side of said blade adapted to engage said edge of said plate in scissors relation, with said blade being cammed outwardly by said plate, as said plate and blade are closed.

4. In a device for applying strips of pressure-sensitive tape: the combination of a presser plate slidably mounted for rectilinear reciprocal movement in directions substantially at right angles thereto, said plate having a cutting edge at one side thereof; a semistationary blade at said side of said plate slidably mounted for rectilinear movement in directions substantially parallel to said plate, said blade having a cutting edge at the side thereof adjacent to said plate which is inclined both to said plate and to a plane at right angles to said plate through said cutting edge of the plate; spring means biasing said blade inwardly relative to said plate; and an adjustable stop means for defining an innermost position of said blade wherein as said plate is advanced the said edge thereof engages said blade progressively in scissors relation and cams said blade outwardly therefrom.

5. In a device for dispensing strips of pressure-sensitive tape from a supply roll and applying said strips to sheets: the combination of presser die plates closable in parallel relation and between which from one side thereof said sheets are inserted; in adjacent relationship to one of said plates, the other of said plates having a cutting edge at the side thereof opposite that from which said sheets are inserted; a blade at said opposite side of said plates having a cutting edge engaged in scissors relation by said edge of said other die plate as said plates are closed, said blade being carried with said one plate and spaced therefrom to provide a clearance space between it and said one plate for said sheets so that the sheets may be inserted beyond the edge of said blade; and means for feeding tape from said roll through the space between said cutting edges with the adhesive side of the tape facing towards said blade.

6. In a device for applying strips of pressure-sensitive tape from a supply roll to sheets: the

combination of a pair of presser die plates closable in parallel relation and from one side thereof said sheets are inserted therebetween in adjacent relationship to one of said plates, the other of said plates having a cutting edge at the side thereof opposite that from which said sheets are inserted; a blade at said opposite side of said plates having a cutting edge for engaging said edge of said other plate as said plates are closed, said blade being carried with said one plate and mounted at a distance therefrom to provide a clearance space between it and said one plate into which said sheets may be inserted beyond the edge of said blade; and means for feeding tape from said roll between said plates from said opposite side thereof with the adhesive side of the tape facing towards said blade.

7. The combination set forth in claim 6 including adjustable stop means for limiting the distance said sheets can be inserted into said clearance space whereby the distance of the applied strip of tape from the edge of the sheet can be preset at different values.

8. In a device for applying strips of pressure-sensitive tape to sheets: the combination of a pair of presser plates closable in parallel relation, one of said plates having a cutting edge at one side thereof and the other of said plates having a portion extending beyond said edge; a blade mounted slidably on said portion for inward and outward movement in directions substantially parallel to said plates; means biasing said blade inwardly; stop means defining the inner position of said blade, and a cutting edge on the inner side of said blade adapted to engage said edge of said one plate in scissors relation as said plates are closed.

9. In a device for dispensing strips of pressure-sensitive tape and applying said strips: the combination of a presser die plate having a cutting edge at one side thereof; a blade at said one side having a cutting edge for engagement with said edge of said plate; means mounting said plate for advance and return movement relative to said blade to engage and disengage said cutting edges; means for feeding tape through the space between said edges with the adhesive side facing towards said blade; actuating means for effecting a relative advance movement of said plate to cut off the fed-out length of tape and apply the same; and means operated by said actuating means during relative advance movement of said plate beyond said blade for breaking the adhesive contact of the tape supply from said blade.

10. In a device for dispensing strips of pressure-sensitive tape from a supply roll and applying said strips: the combination of a presser plate having a cutting edge at one side thereof; a blade at said one side having a cutting edge for engagement with said edge of said plate; means mounting said plate for advance and return movements relative to said blade in directions substantially at right angles to said plate; means for feeding tape from said roll through the space between said cutting edges with the adhesive side of the tape facing towards said blade; and means carried with said plate and operated in response to a relative advance movement of said plate beyond said blade for breaking the adhesive contact of said tape with the cutting edge of said blade.

11. In a device for dispensing strips of pressure-sensitive tape from a supply roll and applying said strips: the combination of a frame; a presser

plate slidably mounted on said frame and having a cutting edge at one side thereof; a blade mounted slidably on said frame for inward and outward rectilinear movement relative to said plate in directions substantially parallel thereto, said blade being at said side of said plate and having a cutting edge on its side adjacent to said plate for engaging said edge of said plate in scissors relation as said plate is advanced past said blade; means for pulling tape from said roll between said cutting edges and across said plate with the adhesive side thereof facing towards said blade; an arm carried with said plate and slidably held against said frame for holding said plate from turning about its direction of movement; means for locking said roll during advance of said plate as an incident preceding the cutting of the tape; and a member on said arm moved across the path of the tape leading from said roll to said blade and effective as said plate is advanced beyond said blade for freeing the tape supply from adhesive contact with said blade.

12. In a device for dispensing strips of pressure-sensitive tape from a tape supply roll and applying said strips: the combination of a presser member mounted for advance and return movements, said presser member having a cutting edge at one side thereof; a member at said side and adjacent to said presser member for backing the non-adhesive side of the tape drawn from said roll; means mounting said backing member for movement in directions of the advance and return movements of said presser member; a blade at said side spaced from said backing member in the direction of advance of said presser member and having a cutting edge for engaging said edge of said presser member as said presser member is advanced; and means for imparting a unitary advance movement to said presser member and said backing member until the latter approaches said blade and thereupon further advancing said presser member while said backing member is held stationary.

13. The combination set forth in claim 12 including means associated with said presser member and coacting with the tape supply as said presser member is advanced beyond the cutting edge of said blade for breaking the adhesive contact of the tape supply with said blade.

14. In a device for dispensing strips of pressure-sensitive tape from a supply roll and applying said strips: the combination of a slidably mounted plunger movable along its longitudinal axis; a presser member fixed to one end of said plunger and having a cutting edge at one side thereof; a tape-feed member for engaging the adhesive side of the tape at said side of said presser member; means slidably mounted on said plunger and extending beyond said side of said presser member for backing the tape engaged by said feed member; means biasing said backing means against said presser member; a blade having a cutting edge at said side spaced from said backing means and engaged by said edge of said presser member as said plunger is advanced; and means for stopping said backing means before the same reaches said blade as said plunger is advanced.

15. In a device for dispensing strips of pressure-sensitive tape from a supply roll and applying said strips to flat surfaces: the combination of a frame member having a bottom portion at right angles thereto provided with an aperture; a presser member mounted for movement through said aperture, said presser member having a cutting edge at one side thereof; a blade at said side

slidably mounted on said bottom portion and having an edge engaged by said presser member as the latter is advanced; means for feeding tape from said roll through the space between said edges and across said presser member; and a depressible plunger coupled with said feeding means and presser member for actuating said feeding means and advancing said presser member in sequence.

16. In a device for dispensing strips of pressure-sensitive tape and applying said strips to flat surfaces: the combination of a tubular plunger slidably mounted for axial movement; a presser plate secured to one end of said plunger; means for feeding tape from said roll across said plate with the adhesive side thereof facing away from said plate; means for cutting off the fed-out length of tape as said plate is advanced; a rod slidably mounted in said plunger for actuating said feed means and plunger; and coupling means between said feed means and plunger for causing the same to be actuated in predetermined sequence.

17. In a device for dispensing and applying strips of pressure-sensitive tape to flat surfaces: the combination of a frame having spaced portions provided with aligned apertures; a plunger mounted slidably in said apertures; a presser member secured to one end of said plunger and having a cutting edge at one side thereof; a bottom wall for said device carried by said frame and having an aperture therein to clear said presser member as said plunger is advanced; a blade mounted slidably on said bottom wall at said side of said presser member and having a cutting edge at the inner side thereof adjacent to said presser member, said blade overhanging the aperture in said bottom wall; means urging said blade inwardly in direction substantially at right angles to the axis of said plunger; and stop means adjustable to define the innermost position of said blade in a position wherein, as said plunger is advanced, the cutting edge of said blade engages said presser member in scissors relation and the presser member thereupon moves through said aperture of said bottom wall.

18. In a device for dispensing strips of adhesive tape from a supply roll and applying said strips: the combination of a frame; a plunger slidably mounted on said frame; a presser member carried on one end of said plunger and having a cutting edge at one side thereof; a cooperable blade movably mounted on said frame for movement transverse to that of said plunger, said blade having a cutting edge engageable in scissors relation by said edge of said presser member as the presser member and blade are closed; means for feeding tape from said roll through the space between said cutting edges and across said presser member with the adhesive side thereof facing away from the latter; and means for actuating said feeding means and closing said presser member and blade in the sequence named.

19. In a device for dispensing strips of pressure-sensitive tape from a supply roll: the combination of a frame; a plunger movably mounted on said frame; a cutting member secured to one end of said plunger; tape feeding means including a member for engaging the adhesive side of the tape drawn from said roll and directing the tape across said cutting member; a member mounted for relative movement with respect to said cutting member and yieldably held in a predetermined position relative thereto for backing the tape contacted by said engaging member when said feed means is in unoperated position; a blade

cooperable with said cutting member as said plunger is advanced, said blade being spaced in the direction of advance of said plunger from said backing member; and means for stopping said backing member before the same reaches said blade as said plunger is advanced.

20. In a device for feeding lengths of pressure-sensitive tape from a supply roll and applying said strips: the combination of a frame; a plunger movably mounted on said frame; a presser member secured to one end of said plunger; tape feed means including a member for engaging the adhesive side of the tape drawn from said roll and directing the tape across said presser member; a member movably mounted on said plunger and normally held in a predetermined position relative to said presser member for backing the tape contacted by said engaging member when said feed means is in unoperated condition; and means coupled to said plunger and backing member for moving the same in unison through a first portion of the stroke of the plunger and for thereupon moving only said plunger.

21. In a device for dispensing lengths of pressure-sensitive tape from a supply roll: the combination of a frame having two spaced bearings; a plunger slidably mounted in said bearings; a cutting member secured to one end of said plunger; a cooperable blade on said frame spaced from said cutting member; a feed mechanism including a feed member movable through the space between said cutting member and blade to pull a length of tape from said roll; a movable member for backing the tape engaged by said feed member when the latter is in initial position; means biasing said backing member against said cutting member; means for stopping said backing member as said plunger is advanced; and an actuating member slidably mounted on said plunger, said actuating member having a lost-motion connection to said plunger and a coupling to said feed mechanism adapted for operating the feed mechanism and plunger in sequence.

22. The combination set forth in claim 21, wherein said backing member is interposed between said cutting member and the adjacent one of said bearings, and is provided with a portion straddling said one bearing and cooperable therewith to limit the movement of the backing member to less than that of said plunger, and wherein said biasing means is connected between said plunger and said backing member.

23. In a device for dispensing lengths of pressure-sensitive tape from a supply roll: the combination of a frame; a plunger slidably mounted on said frame; a cutting member secured to one end of said plunger; a cooperable blade spaced from

said cutting member and mounted on said frame; a feed mechanism including a feed member movable through the space between said cutting member and blade to pull a length of tape from said roll; an actuating member slidably mounted against said plunger and coupled to said feed mechanism to operate the same as the actuating member is moved through the first part of its stroke; a lost-motion coupling between said plunger and actuating member for causing the latter to operate the former through the latter part of the advance stroke thereof; and an interlock between said plunger and feed mechanism and operated by said actuating member for positively retaining said plunger in unoperated position during operation of said feed mechanism and for locking said plunger to said actuating member during the stroke of the latter following operation of said feed mechanism.

24. In a device for dispensing lengths of pressure-sensitive tape from a supply roll: the combination of a frame; a plunger slidably mounted on said frame; a cutting member on one end of said plunger; a reciprocable feed member movable from an initial position through the space between said blade and cutting member to pull a length of tape from said roll and returnable to said initial position; pivoted means on said frame carrying said feed member including a lever straddling said plunger, an actuating member slidably mounted on said plunger, the opposite legs of said lever having cam slots engaged by said actuating member, said slots being arranged to cause said feed member to be advanced and returned by forth and back movements of said actuating member through a first part of its stroke, and to retain said feed member in operated position during the latter part of its stroke; and means operative only during the latter part of the stroke of said actuating member for interlocking the same with said plunger.

GEORGE H. FRITZINGER.
